UNITED STATES PATENT OFFICE.

GEORGE F. HANDLEY, OF GLENDALE, NEW YORK, ASSIGNOR TO ROYAL TYPEWRITER COMPANY, INC., OF NEW YORK, N. Y., A CORPORATION OF NEW YORK.

TYPEWRITING MACHINE.

Application filed May 27, 1922. Serial No. 564,099.

To all whom it may concern:

Be it known that I, GEORGE F. HANDLEY, a citizen of the United States, residing in Glendale, in the county of Queens and State 5 of New York, have invented certain new and useful Improvements in Typewriting Machines, of which the following is a specification.

This invention relates to the platens of 10 typewriting machines, and the object of the invention is to provide a supplemental or auxiliary platen of novel construction which is so associated with the main platen that it can be rapidly brought into service when 15 multiple manifolding is desired or when the main platen is not sufficiently hard or firm to produce multiple manifolds.

It is generally desirable to use a soft platen for ordinary service when only a few 20 carbon copies are needed as less noise is produced when a soft platen is used, but in such cases it has hitherto usually been the custom to detach the soft platen from the machine and replace it by a hard platen when 25 many carbons are needed. This is difficult for some operators to do and consumes considerable time. These difficulties have been overcome by the use of an auxiliary platen which is so applied to the machine that it 30 may be moved from an inactive to an active position either directly or by frictional contact with some part of the main platen. This invention is shown, described, and claimed in an application of Edward B. 35 Hess, filed April 21, 1922, Serial No. 555,853. Said application shows a strip of relatively hard metal extending from end to end of the main platen and connected at its ends to devices for locking it in active and inactive 40 positions and for preventing overthrow. Such invention is, therefore, not herein broadly claimed, but according to my invention improved means are provided for moving the auxiliary platen from one position to another for locking it in active and inactive positions and for preventing overthrow and for maintaining a perfect register 45 of the auxiliary platen with the main platen.

In carrying out my invention in the preferred way I provide means at opposite ends of the main platen for supporting the opposite ends of the auxiliary platen and for producing such friction between these parts that the auxiliary platen may be 50 moved from active to inactive position and

vice versa by turning the main platen. In such case there is not necessarily a frictional engagement between the auxiliary platen and the cylindrical surface of the main platen. I have also added to the mechanism 60 a device for preventing any possibility of overthrow when the auxiliary platen is moved to active or inactive position and this device also serves to hold the auxiliary platen accurately in the line of print in active position when thus located. 65

In the accompanying drawings:

Figure 1 is a view of a main or cylindrical platen with my improvements applied, some parts being shown in elevation and 70 some in section and some parts being broken away for clearness of illustration.

Figure 2 shows a transverse section on the line 2—2 of Figure 1.

Figure 3 is a detail view on an enlarged 75 scale showing particularly the devices for obtaining frictional contact between the auxiliary platen and the main platen whereby the auxiliary platen may be moved coincidentally with the main platen or may be 80 moved independently thereof.

Figure 4 is a diagrammatic illustration in plan of certain features of construction at one end of the platen.

Figure 5 is a side view of some of the 85 parts illustrated in Figure 4.

In Figures 4 and 5 the parts illustrated are shown in the active position of the auxiliary platen.

Figures 6 and 7 are views similar to Figures 4 and 5, the mechanism being shown in the inactive position of the auxiliary platen.

The main platen, parts of which are shown in Figure 1, comprises a shaft A, a shell B, a covering C of soft material, hubs D and E, and frictional line spacing devices F. These parts may be of any suitable construction. The ratchet wheel for the line spacing is indicated at G, and H indicates parts of the end plates of the carriage frame. 100

The auxiliary platen K preferably consists of a narrow strip of hard material, preferably metal, which extends from end to end of the main platen and may lie in frictional contact therewith or as shown may 105 be held a short distance from the cylindrical surface thereof. The strip on its inner and outer sides has a curved surface corresponding with the curvature of the platen and on its outer side it is smooth and so shaped as to 110

correspond with the curved characters on the type bars. The opposite ends of the auxiliary platen are supported by devices which are mounted to turn about the axis of the main platen. Preferably these devices are connected with the hubs of the main platen and the arrangement is such that the auxiliary platen may be moved from one position to another by reason of the frictional engagement of the supports of the auxiliary platen and parts of the main platen, it being understood that in this connection the platen shaft is considered a part of the main platen. Various devices may be employed for the purposes above mentioned, but as shown the right hand end of the auxiliary platen is connected by an arm *l* to a ring *L* surrounding the platen hub *E* and freely movable thereon. The ring *L* is engaged by a spring *M* surrounding the hub and engaging the adjacent end plate *c* of the main platen. The spring *M* presses the ring *L* against a collar *N* secured to the platen shaft by a set screw *O* which extends through the collar and the hub and engages the shaft. In this way the desired friction is produced between one of the supports of the auxiliary platen and a part of the main platen so that when the main platen is turned, the auxiliary platen is correspondingly moved when desired, but when required the auxiliary platen may be moved independently of the main platen.

The opposite end of the auxiliary platen is secured to a ring *P* surrounding the platen hub *D*. The inner diameter of this ring is somewhat greater than the diameter of the hub *D* and it is supported by spring plungers *Q* arranged radially in the hub and normally projecting a short distance therefrom. Any desired number of plungers may be employed, but three as indicated in Figure 2 have been found to be sufficient. It will be observed by reference to Figure 3 that the plungers *Q* are formed on their outer ends with grooves *q* in which the ring *P* is seated. This construction permits a slight endwise movement of the auxiliary platen to allow the spring *M* at the opposite end of the platen to properly function. In this way a frictional engagement between the auxiliary platen and the main platen is produced whereby the auxiliary platen may be moved if desired coincidentally with the main platen. The devices shown at the left hand end of the platen may be also used at the right hand end, but I prefer to employ there the devices before described.

In order to lock the auxiliary platen in active and in inactive positions I employ a pawl *R* pivotally mounted on the carriage frame in any suitable way. As shown, the pawl is attached to a rod *S* which may be mounted in the carriage in suitable bearings as indicated in Figures 5 and 7. The pawl is provided with a handle *r* and with

stops *r'*, *r''* adapted to engage the frame and limit the movement of the pawl in both directions. The toothed end *t* of the pawl is pulled downward by a spring *s*.

The tooth *t* of the pawl *R* is adapted to engage either one of the notches *u* or *u'* in the ring *P*. When it engages the notch *u* the auxiliary platen is locked in active position (Figure 5) in the line of print. When the tooth *t* engages the notch *u'*, the auxiliary platen is locked in inactive position (Figure 7).

It will be observed that the front and rear walls of the notches *u*, *u'* are straight and parallel and when engaged with the tooth *t* of the pawl are tangential to the axis of the main platen. The front and rear walls of the tooth *t* are similarly shaped so that when the pawl is engaged in a notch, no movement of the auxiliary platen can take place, but the main platen is free to turn in the usual way. By lifting the pawl from the engaged notch, the auxiliary platen may be turned from inactive to active position or vice versa by merely operating the knobs or handles of the main platen and when positioned, the pawl will lock the auxiliary platen so that the main platen may be turned in the usual way without disturbing the auxiliary platen.

If desired, the auxiliary platen may be used as an erasing plate by turning it to the desired position and holding it frictionally by the devices above described.

In order to prevent overthrow of the auxiliary platen and to insure of its proper register in the line of print, I employ the devices shown in Figures 4 to 7 inclusive. As illustrated, a stop *V* is carried by the ring *P* in suitable position to be engaged by an auxiliary pawl *W* which co-operates with the pawl *R*. The stop *V* is formed with a bevelled end *v* with which the pawl *W* engages when the auxiliary platen is in active position and its front end is adapted to engage the auxiliary platen in the manner shown in Figures 6 and 7 when said auxiliary platen is in inactive position. The pawl *W* when engaged with the auxiliary platen in its inactive position serves as a stop to prevent any danger of overthrow and does not, therefore, strictly speaking, act as a pawl but more correctly as a stop to prevent accidental overthrow when the auxiliary platen is moved rapidly or forceably forward or rearwards.

The accidental forward movement of the auxiliary platen when in inactive position is prevented by the pawl *R* which locks it in place. When the auxiliary platen is moved to active position (Figures 4 and 5) the pawl *R* engages the bevelled end of the stop *V* and prevents overthrow after the auxiliary platen has moved forward and co-operates with the pawl *R* in holding the auxiliary platen in perfect register with the

main platen and with the curved faces of the type. Preferably the device W takes the form shown in the drawings, consisting of a metal strip riveted to the pawl R in the manner shown, but its functions may be performed by devices of various kinds.

It will be observed that the tooth of the pawl W is somewhat longer than the tooth t of the pawl R.

10 In order to cause the toothed end of the pawl R to properly engage the notch u or u' it is desirable that the parts should not be made too long or too deep. Inasmuch as the pawl swings about an axis in rear of the platen, there is some danger of the pawl rising and being disengaged from the notches, but this danger is compensated by the parts W and V when functioning in the manner before described.

15 20 I claim as my invention:—

1. In a typewriting machine, the combination of a main platen and an auxiliary platen associated therewith and movable from an inactive position removed from the line of print to an active position in the line of print, and spring controlled means for maintaining yielding frictional connection between the two platens.

2. In a typewriting machine, the combination of a main platen and an auxiliary platen associated therewith and movable from inactive position removed from the line of print to active position in the line of print, means for yieldingly supporting one end of the auxiliary platen on the main platen, and devices for supporting the opposite end of the auxiliary platen comprising a ring surrounding a part of the main platen and spring pressed devices interposed between said ring and the main platen.

3. In a typewriting machine, the combination of a main platen and an auxiliary platen associated therewith and movable from an inactive position removed from the line of print to active position in the line of print, means for supporting the auxiliary platen yieldingly at one end of the main platen, and means for supporting the auxiliary platen at the opposite end of the main platen comprising a ring and spring pressed plungers carried by the main platen.

4. In a typewriting machine, the combination of a main platen and an auxiliary platen having supports at opposite ends mounted to turn about the axis of the main platen, and means for exerting yielding pressure on one of said supports in all positions of the auxiliary platen.

5. In a typewriting machine, the combination of a main platen and an auxiliary

platen having supports at opposite ends mounted to turn about the axis of the main platen, and means for exerting yielding pressure on both supports in all positions of the auxiliary platen.

65

6. In a typewriting machine, the combination of a main platen and an auxiliary platen having supports at opposite ends mounted to turn about the axis of the main platen, a collar on a hub of the main platen, and a spring interposed between one of the supports and the end of the platen to yieldingly press said support against the collar.

70

7. In a typewriting machine, the combination of a main platen and an auxiliary platen having supports at opposite ends mounted to turn about the axis of the main platen, and radially movable spring pressed devices engaging the support at one end to afford a yielding frictional connection between the main platen and the auxiliary platen.

75

8. In a typewriting machine, the combination of a main platen and an auxiliary platen associated therewith and movable from an inactive position removed from the line of print to active position in the line of print, means for locking the auxiliary platen in inactive position, and devices for preventing overthrow when the auxiliary platen is moved to inactive position.

80

9. In a typewriting machine, the combination of a main platen and an auxiliary platen movable to active and inactive positions relatively to the line of print, means for locking the auxiliary platen in inactive position, and an auxiliary device carried by the locking means and engaging the auxiliary platen for preventing overthrow thereof.

85

10. In a typewriting machine, the combination of a main platen and an auxiliary platen movable to active and inactive positions relatively to the line of print, means for locking the auxiliary platen in inactive position, and an auxiliary device carried by the locking means and engaging the auxiliary platen for holding it in active position.

90

11. In a typewriting machine, the combination of the main platen and an auxiliary platen movable to active and inactive positions, detent devices for locking the auxiliary platen in its adjusted positions, and means carried by the detent devices for preventing overthrow and for holding the auxiliary platen in register with the main platen when in active position.

95

In testimony whereof, I have hereunto subscribed my name.

GEORGE F. HANDLEY.
